United States Patent Office.

EDWIN CHARLES RUTHVEN, OF PHILADELPHIA, PENNSYLVANIA, ASSIGNOR TO
MACKELLAR, SMITHS & JORDAN, OF SAME PLACE.

Design No. 3,389, dated February 23, 1869.

DESIGN FOR PRINTERS' TYPE.

The Schedule referred to in these Letters Patent and making part of the same.

To all whom it may concern:

Be it known that I, EDWIN CHARLES RUTHVEN, assignor to MACKELLAR, SMITHS & JORDAN, of the city and county of Philadelphia, Pennsylvania, have invented or produced a new Design for Printing-Type, of which the following is a full, clear, and exact description, reference being had to the accompanying specimens, making part of this specification, in which the entire alphabet of capital letters is shown, as well as several numerals, in which my design is clearly illus-

trated, and which design is preserved in the small letters of the alphabet, and in any other signs or symbols made.

Having thus described my invention,

What is claimed is—

The within-described design for a printing-type.

E. C. RUTHVEN.
